UNITED STATES PATENT OFFICE.

BARNARD B. COULTAS AND ERNEST J. STANLEY, OF BAKERSFIELD, CALIFORNIA.

ROD OR WELL-CASING ELEVATOR.

Application filed December 2, 1921. Serial No. 519,498.

To all whom it may concern:

Be it known that we, BARNARD B. COULTAS and ERNEST J. STANLEY, citizens of the United States, residing at Bakersfield, in the county of Kern and State of California, have invented a new and useful Rod or Well-Casing Elevator, of which the following is a specification.

This invention has reference to rod or well-casing elevators for use in connection with deep wells and its object is to provide means whereby the structure may be readily adapted for either sucker rods or well casings, requiring but a minimum change to adapt it to either purpose.

In accordance with the invention, there is provided a holder with a rotatable member, both the holder and rotatable member having entering slots arranged to match each other, with the rotatable member swivelled axially of and to the holder and interlocked therewith against longitudinal movement so that the slots may be moved with relation to each other, so as to cross, and the two relatively rotatable members are so connected that they may be locked in chosen angular relation to each other to receive and hold a latch capable of locking the holding and rotatable members together and thereby prevent movement of the rotatable member about its axis of rotation sufficiently to permit the escape of the coupling usually employed to connect the adjacent ends of the sucker rod or of the well casing. In this manner, when it is desired to withdraw the sucker rod or well casing, the elevating structure is connected and locked to the upper end of the sucker rod or well casing and then, by the employment of suitable apparatus, the rod or casing is withdrawn from the well without danger to the workmen.

The invention will be best understood from a consideration of the following detailed description taken in connection with the accompanying drawings forming part of this specification, with the understanding, however, that the invention is not confined to any strict conformity with the showing of the drawings, but may be changed and modified so long as such changes and modifications mark no material departure from the salient features of the invention as expressed in the appended claims.

55 In the drawings—

Fig. 1 is an elevation of the elevating tool

in position to engage a sucker rod or a well casing;

Fig. 2 is a longitudinal section through the structure of Fig. 1;

Fig. 3 is a plan view of the structure of Fig. 1;

Fig. 4 is a longitudinal section at right angles to the showing of Fig. 2;

Fig. 5 is an elevation of the structure as viewed from the right hand side of Fig. 4;

Fig. 6 is a plan view, partly in horizontal section of the structure shown in Figs. 4 and 5.

Referring to the drawings, there is shown an incomplete, cylindrical or sleeve-like holder 1, having trunnions 2, and at diametrically opposite sides receiving eyes 3 of a link or bail 4, the eyes 3 being sufficiently spread apart to be entered and traversed by the trunnions 2. Any appropriate means may be employed to hold the link 4 on trunnions 2, as, for instance, cotter or other pins 5.

The holder 1 is formed with a radial slot 80 or recess 6, entering the holder from one side and the trunnions 2 are located about midway of the length of the holder or body member 1, the recess 6 is of a width to receive a coupling 7 screwed onto one end of a sucker rod 8, or other element, such as a length of casing, to be elevated or withdrawn from the well.

It is customary to form the coupling 7 with diametrically opposite depressions 9 90 for the application of a wrench, by means of which the sleeve or coupling 7 may be manipulated in joining the sucker rod or casing elements together. The coupling 7 turns about its longitudinal axis in the recess 6.

Swivelled to one end of the body member 1 is a ring-shaped member 10 which may, in the main, be concentric with the body member, and is provided on one side with a finger or tongue 11 in the path of which is another finger or tongue 12 limiting the degree of rotative movement of the ring 10 with relation to the body member 1 by the engagement of the finger 11 with the finger 12. 100

The sleeve or coupling 7 is of reduced diameter at diametrically opposite sides where the depressions 9 occur and this reduced diameter corresponds to the width of a slot 13 diametric to the ring 10. The slot 13 may 110 be brought into coincidence with the slot 6 but is narrower than the slot 6 and corre-

responds to the spacing of the sides of the recess 13 so that if the slots 6 and 13 coincide, both being entering slots, the sleeve or coupling 7 where provided with the depressions 9, may be slipped into the matching slots to one side of the holder 1, and then by turning the ring 10 axially the coupling 7 with the rod 8, or a well casing when present, is anchored or locked in the holder 1 and supported axially therein.

In order to connect the ring 10 to the upper end of the body member 1, the latter is provided with an undercut or dove-tailed tongue 14, and the ring 10 has a dove-tailed or undercut channel 14^a into which the dove-tail 14 fits, thereby holding the parts together for relative rotation without escape one from the other, and also permitting the assemblage of parts without difficulty, for the ring 10 may be conveniently formed of two similar parts united by a bolt or rivet 15, which in conjunction with the dove-tailed part holds the divided ring in swiveled relation to the body member 1. To facilitate of the turning of the ring 10, and the parts carried thereby, the body member 1 is finished on one side with a radial handle 16, by means of which the body member 1 may be turned about its longitudinal axis so that the slots 6 and 13 may be brought into matching relation to each other in such manner as to cross and thereby lock the coupling 7, or other similar part, against escape.

In order to accomplish this, there are provided on the body member 1, beneath the handle 16, two adjacent ears 17 and 18, between which is hinged a thumb latch 19, the ear 17 being longer than the ear 18 and reaching from the ring 10 to the handle 16 for the purpose of strength. Pivoted to the latch 19 is a slideable bolt 20, guided in a slot or recess 21 in the body member 1 out of the path of the bolt 20 but movable into the path thereof so as to engage one side of the recess 13, and thus prevent turning of the ring 10. The latch 19 is constrained by a spring 22 to normally move into the path of the ring 10.

In order to attach the elevator to the sucker rod 8, or to the well casing or tubing, the slots 6 and 13 are set in alinement so as to receive the coupling 7 from one side of the body member 1 and ring 10 by way of the recesses 9 on opposite sides of the coupling, whereupon by an appropriate rotation of the ring 10, the coupling 7 becomes locked in place and with suitable tackle (not shown) attached to the elevator, the rod 8 or the well casing, or whatever is being acted upon, is made fast against liability of escape and may be withdrawn from the well or inserted thereunto as desired.

What is claimed is—

65 1. Elevating means for use in connection

with sucker rods or other parts, comprising a body member with a radial recess therein extending axially therethrough and of a size to pass a coupling at the end of a length of a sucker rod, a ring swiveled to one end of the body member and provided with a radial recess movable across the recess in the body member, and a latch for coupling the body member and the ring together to prevent the escape of the coupling while the sucker rod is being elevated.

2. Elevating means for use in connection with sucker rods or other parts, comprising a substantially cylindrical body member having a radial recess opening through one side thereof, a ring at one end of the body member having a dovetailed tongue on one face and the ring having a dovetailed groove to receive the tongue to hold the ring to the body member, the ring also having a radial slot movable into and out of coincidence with the slot in the body member, with the slot in the ring of less width than the slot in the body member, coacting fingers on the body member and ring serving as stops, a latch, a manipulating means therefor carried by the body member and engaging the ring, and a link or bail carrying the body member on opposite sides of the recess therein.

3. Elevating means for use in connection with sucker rods and other parts, comprising a body member with a radial slot or recess in one side and trunnions on the body member at diametrically opposite sides of said body member, a ring at one end of the body member formed of two half rings with the ring and body member at one end having the meeting portions joined by interlocking swivel connections, said ring having a radial slot or recess movable into crossing relation to the radial recess in the body member, a latch for coupling the body member and ring together with the recesses in line with each other, or relatively displaced, and a link supporting the body member by the trunnions.

4. Elevating means for use in connection with sucker rods or other parts, comprising a body member with a radial slot or recess in one side, a ring at one end of the body member formed of two axially connected half rings with the ring and body member at one end having the meeting portions joined by an interlocking swivel connection, and a latch for coupling the body member and ring together and provided with stops on the ring and body member respectively, for limiting the relative rotation of the ring and body member to a predetermined extent.

5. Elevating means for use in connection with sucker rods or other parts, comprising a body member with a radial slot or recess in one side, a ring at one end of the body

member formed of two axially connected half rings with the ring and body member at one end having the meeting portions joined by an interlocking swivel connection, and a latch for coupling the body member and ring together and provided with stops on the ring and body member, respectively, for limiting the relative rotation of the ring and body member to a predetermined extent, the ring being formed of two pieces joined at one side opposite the entering end of the recess by a rivet or bolt and the body member and ring having coacting means for connecting the ring and body member when the recesses are in crossing relation.

6. Elevating means for use in connection with sucker rods or other parts, comprising a body member with a radial slot or recess in one side, a ring at one end of the body member formed of two axially connected

half rings with the ring and body member at one end having the meeting portions joined by an interlocking swivel connection, and a latch for coupling the body member and ring together and provided with stops 25 on the ring and body member respectively, for limiting the relative rotation of the ring and body member to a predetermined extent, the ring being formed of two pieces joined at one side opposite the entering end 30 of the recess by a rivet or bolt and the body member and ring having coacting latch means active to hold the recesses in crossing relation.

In testimony that we claim the foregoing 35 as our own, we have hereto affixed our signatures.

BARNARD B. COULTAS.
ERNEST J. STANLEY.
